[57] CLAIM

The ornamental design for a revolving super structure for a crane, as shown.

DESCRIPTION

FIG. 1 is a side elevational view of a revolving super structure for a crane showing my new design, the opposite side being substantially a mirror image thereof.

FIG. 2 is a top plan view thereof.

FIG. 3 is a bottom plan view thereof.

FIG. 4 is a front elevational view thereof.

FIG. 5 is a rear elevational view thereof.

FIG. 1

FIG. 2

FIG. 3

FIG. 4

FIG. 5
